UNITED STATES PATENT OFFICE.

ARTHUR A. BULL, OF DETROIT, MICHIGAN, ASSIGNOR TO GENERAL MOTORS CORPORATION, OF DETROIT, MICHIGAN, A CORPORATION OF DELAWARE.

GOVERNOR FOR INTERNAL-COMBUSTION ENGINES.

Application filed July 26, 1920. Serial No. 398,912.

To all whom it may concern:

Be it known that I, ARTHUR A. BULL, a subject of the King of Great Britain, and a resident of Detroit, county of Wayne, and 5 State of Michigan, have invented certain new and useful Improvements in Governors for Internal-Combustion Engines, of which the following is a full, clear, concise, and exact description, such as will enable others skilled in the art to which the invention relates to make and use the same, reference being made therein to the accompanying drawings, which form a part of this specification.

My invention relates to internal combustion engines, and particularly to automatic governor mechanism therefor designed to regulate the speed of the engine by controlling the flow of combustible mixture thereto.

The principal object of my invention is 20 to provide improved governor mechanism for internal combustion engines whereby the speed thereof may be maintained constant when in operation, the mechanism in question employing a centrifugal governor as a part thereof and the speed of the engine being governed by throttling the supply of combustible mixture thereto.

A further object of my invention is to 30 provide improved automatically operating governor mechanism for controlling the speed of internal combustion engines and wherein the governor mechanism in its entirety may be regarded as made up of two separate units, each independent of the other and each capable of being manufactured, assembled and adjusted apart from the other and apart from the engine with which it may subsequently be used; one of said units comprising a centrifugal governor device 40 responsive to variations in the speed of the engine when the same is in use, and the other comprising a throttle valve device for controlling the flow of combustible mixture through a passage which leads to the engine; the two units thus provided being subsequently attached to the engine with which they are to be used and connected with one another so that the valve device in question 50 will be controlled by the centrifugal governor mechanism referred to.

A further object of my invention is to 55 provide improvements in and relating to various sub-combinations of elements, and various auxiliary parts, elements, and features of governor mechanism of the class to

which this application relates, all as will more fully and at length hereinafter appear.

With the above and other objects of invention in view, my invention consists in the improved governor mechanism for internal 60 combustion engines illustrated in the accompanying drawings and hereinafter described and claimed; and in such variations and modifications thereof, within the scope of the concluding claims, as will be obvious to 65 those skilled in the art to which my invention relates.

Referring now to the drawings accompanying and forming a part of this specification and wherein the preferred embodiment of my invention is illustrated:

Figure 1 is a view illustrating an internal combustion engine in side elevation, the same being equipped with governor mechanism made in accordance with my invention, the view being employed to show the arrangement of the parts which form the speed controlling mechanism relative to one another and to the engine.

Figure 2 is a fragmentary view upon a 80 larger scale showing the governor mechanism as seen from a position to the right of Figure 1, the view being partly in elevation and partly in section upon a transverse plane central relative to the engine, and passing 75 through the throttle valve and parts directly connected therewith.

Figure 3 is a view for the most part in section showing the centrifugal governor unit of my improved governor mechanism 90 by itself, and upon a vertically extending plane extending longitudinally thereof and indicated by the line 3, 3, Figure 2.

Figure 4 is a view showing the inlet and exhaust manifolds and the throttle valve unit of my improved governor mechanism 95 in side elevation, together with the operating mechanism for the throttle valve in section upon a vertically extending plane indicated by the line 4, 4, Figure 2.

Figure 5 is a view showing the throttle valve unit of my improved governor mechanism in plan, and as seen looking downward from the plane 5, 5, Figures 2 and 3.

Figure 6 is a view showing the means for 105 adjusting the throttle valve and for locking the operating means therefor and sealing the same after it has been properly adjusted in elevation, and as seen from a position to the right of Figure 5.

Figure 7 is a view showing a modified form of locking mechanism for locking the disc whereby the throttle valve is adjusted in position.

- 5 Figure 8 is a view showing a section of the centrifugal governor unit or device of my invention upon a horizontal plane indicated by the line 8, 8, Figures 2 and 3.

Figure 9 is a view showing a section of the said governor device upon a vertical plane indicated by the line 9, 9, Figures 3 and 8.

15 Figure 10 is a fragmentary view showing the gear cover plate opening provided for the centrifugal governor unit of my improved governor as closed by a plate, as is done when the engine is not to be provided with automatically operating governor mechanism.

- 20 Referring to the drawings, the reference numeral 11 designates an internal combustion engine of any suitable type such, for example, as of the multiple cylinder type with cylinders arranged parallel with one another, 12 the head thereof, 13 the supply manifold through which a combustible mixture formed by a carburetor 14 flows to the various cylinders of the engine, and 15 the exhaust manifold through which the exhaust gases flow from the engine; the supply and exhaust manifolds 13, 15 being located both upon one side of the cylinder block and the same being formed as a single integral structure in the engine illustrated in Figure 1.

25 35 The end of the crank case 16 of the engine or of a gear compartment thereof is closed by a gear cover 17 adjacent or within which the gearing which operates the camshaft of the engine is located, but which gearing is not illustrated in detail as the same forms no part of the invention to which this present application relates; and the said gear cover or casing 17 is provided with a projecting portion 18 which extends beyond the side 40 45 wall of the cylinder block as best shown in Figure 2 and is provided with an opening over which the hollow housing 19 of the centrifugal governor mechanism or unit of my improved governor device is secured as by means of bolts 20; the said housing and, as necessarily follows, the centrifugal governor unit of my improved governor being supported by the gear cover or casing 17 in a position offset from the plane of the adjacent side wall of the cylinder block and crank case of the engine, as will be appreciated. As stated above, the gearing through which the cam shaft and often the igniting mechanism, the fan, and other auxiliary elements of the engine are operated is covered by the gear cover 17, and said gearing is commonly made up of several gears one of which is designated by the reference numeral 21; which gear 21 is in mesh with a pinion 22 secured to a sleeve 23 which is rotatably 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880

supported upon a stud shaft or bearing 24 carried by the housing 19 and extending inward toward the gearing aforesaid, the shaft being shown as extending through the open side of the housing which registers with the 70 opening in the cover and the pinion 22 as located beyond the plane of the open side or end of the housing.

The pinion 22 is secured to and acts to drive the sleeve 23 in the embodiment of 75 my invention illustrated; and the reference numeral 124 designates a ball cage formed, preferably, from a comparatively thin sheet metal blank suitably shaped to provide a plurality of laterally extending trough-like 80 pockets or recesses 25, see Figure 9, within each of which a ball 26 is located; the outer ends of said chambers or pockets being inclined, as shown at 125 in Figure 3, so that as the said balls are thrown outward by centrifugal force due to the rotation of the ball cage they will co-operate with said inclined portions to force an annular plate or disc 27 which they engage to the right. The annular plate or disc 27 surrounds the sleeve 90 23 and is carried by a sleeve 28 which is slidable upon the sleeve 23, and 29 designates a flange or washer which is in engagement with the two side arms 30 of an oscillating bifurcated yoke the lower end of 95 which is secured to a sleeve 31. The sleeve 31 is loosely supported upon a shaft 32 the ends of which are supported in lugs 33, 33 extending from the housing 19, see Figure 9; and the upper end 34 of this bifurcated yoke is provided with an eye through which a sleeve nut 35 extends, said nut being in threaded engagement with a rod 36 and the same having trunnions 37 which fit into recesses provided in the upper ends of 100 the yoke, as best shown in Figure 3, said sleeve being rotatable as by means of a screw driver inserted through an opening 38 to thereby adjust the parts in assembling the governor mechanism and vary the effective 105 length of the controlling rod 36. After the parts are properly adjusted the opening 38 is preferably closed by an expandable plug 39 to thereby prevent the sleeve 35 from being rotated and the proper adjustment of 110 the parts disturbed by unauthorized or inexperienced persons.

Suitable ball bearings 40 are preferably provided between the annular disc 27 and the washer 29 to reduce the friction between the parts, and the ball cage 124 is provided with lugs 41 shown as formed integrally therewith and which enter slots 42 provided for their reception in the hub of the pinion 22; from which it will be appreciated that rotary motion imparted to the pinion 22 from the gear 21 with which it meshes will drive the ball cage through the lugs 41 whereupon the balls 26 will be thrown outward and into engagement with the inclined 130

- portions 125 of the recesses wherein said balls are contained, thus moving the annular plate 27 to the right and swinging the bifurcated yoke 34 about the pivotal connection at the lower end thereof provided by the pin 32, the sleeve 28 which carries the ball bearing 40 being slidable upon the rotating sleeve 23. This movement of the bifurcated yoke moves the rod 36 to the right and 10 operates a throttle valve associated with the mixture supply conduit which leads to the engine to thereby regulate the flow of combustible mixture to the engine, as will next appear.
- 15 The reference numeral 43 designates a disc which rotates with the ball cage 124 and the periphery of which moves close to the inner wall of an annular flange 44 at the open side of the housing 19, which flange fits into the 20 opening in the gear cover or casing 17 provided for said housing, as shown in Figures 3, 8 and 9; the purpose of said disc being to prevent portions of the centrifugal governor mechanism which is assembled within 25 the hollow housing 19 from escaping therefrom and passing into the chamber within which the valve operating gear mechanism is located should any of the parts of the centrifugal governor mechanism become 30 broken or disengaged when the engine is in operation.
- The reference numeral 45 designates the casing or housing of the throttle valve unit of my improved governor mechanism, the 35 upper end thereof being connected with the inlet manifold 13 of the engine in any way as by means of suitable bolts 46 while the lower end of said housing is adapted to be connected with the carburetor 14, said housing having a passage 47 through which combustible mixture flows to the engine and having also preferably a heating chamber 48 through which exhaust gases from the exhaust manifold 15 may pass through a suitable 45 conduit to thereby heat the combustible mixture passing through the element in question.
- The housing 45, it will be observed, is a structure separate from the carburetor and 50 intake manifold, so that it provides a unitary device independent of the engine with which the throttle valve and mechanism associated therewith may be assembled to thereby provide a unitary throttle valve device, and 55 said housing is provided with a cylindrical portion 49 extending from the rear wall thereof whereby a chamber 50 is provided the open end of which is closed by a cover 51; said cover having an inwardly extending flange 52 provided with a circumferentially 60 extending groove into which the end of one or more screws 53, see Figure 7, extends, so that the cover may be rotated within the open end of the chamber 50 within which the 65 flange 52 fits. The periphery of this cover is provided with a series of notches 54; and the reference numerals 55 designate bolts extending into ears 56 in the projecting portion 49, and the position of which bolts is such that the shanks of the bolts just under 70 the heads lie within the recess 54 to thereby prevent rotation of the cover 51; the said bolts being provided with holes through which a wire 57 may pass the ends of which are fastened together by a seal 57' to thereby 75 seal the cover in place and in proper position after the governor mechanism has been properly adjusted as will hereinafter and at length appear.
- Figure 7 illustrates a modified form of 80 locking arrangement in which a locking bolt 58 so located as to lie within one of the recesses 54 of the cover is employed, which bolt is supported in passages provided in lugs 59, and is locked to the cylindrical portion 49 by a lock 60 the hasp of which extends through a hole provided in the said bolt.
- The reference numeral 61 designates a 85 throttle valve which is supported by an oscillating shaft 62 and whereby the flow of combustible mixture through the passage 47 may be controlled. The shaft 62 is supported in bearings provided in the housing 45 of the throttle valve unit, and the inner 90 end of said shaft extends into the chamber 50 and is provided therein with an arm 63 angularly adjustable thereupon, as shown in Figure 4. Also located in the chamber 50 is a spring 64 the inner end of which is connected with the oscillating shaft 62 as shown at 65, Figure 2, while the outer end of said spring is connected with the inwardly extending ledge 52 of the cover 51, as indicated at 66 in Figure 4; from which it follows 100 that the tension exerted by the spring 64 upon the throttle valve shaft 62 and through said shaft and the arm 63 upon the rod 36 which is pivotally connected with the free end of the said arm at 67, may be varied by 105 rotating the cover 51 within the open end of the housing 49; and that after the tension of the spring has been properly adjusted the cover may be locked in position by the bolts 55 or the rod 58, which holding element may be then locked and sealed in position as above explained to thereby prevent the tension of the spring and the adjustment of the governor mechanism as a whole from being disturbed by unauthorized persons after 110 the parts have been once properly adjusted.
- The rod 36 through which motion of the oscillating yoke 34 is communicated to the arm 63 and to the throttle valve shaft 62 is 115 preferably enclosed by a tube 68 extending between and the ends of which are supported in recesses one in the housing 19 of the centrifugal governor unit of my governor mechanism, and the other in a boss provided upon the extending cylinder portion 120 125 130

49 of the throttle valve unit of the governor mechanism; and Figure 10 shows how the opening provided for the reception of the centrifugal governor unit of my improved 5 governor mechanism may be closed by a auxiliary plate 69 if the engine is not to be equipped with an automatic governor, thus providing an engine in which one and the same gear casing 17 may be used irrespective 10 of whether or not the engine is equipped with automatic governing mechanism for controlling the flow of combustible mixture thereto.

15 In view of the premises it will be appreciated that the entire centrifugal governor mechanism of my improved speed governor may be assembled with the housing 19 provided therefor, and while said housing is in no way connected with the engine; thus permitting 20 the mechanism in question to be properly assembled and adjusted and subsequently handled as a unit entirely separate from the engine with which it may eventually be used. In the same way all the elements concerned with the regulation of the flow of combustible mixture through the supply passage 47 may be assembled and adjusted relative to one another and relative to the housing 45, thus providing a throttle 25 valve unit complete in itself and one which may be manufactured, assembled and adjusted independently of the engine, and thereafter used as a part of a complete engine; the engine thus provided being equipped with a centrifugal governor unit complete in itself and likewise with a throttle valve complete in itself, and the two mechanisms being connected together by means of a rod like the rod 36 of proper 30 length, no adjustment of the centrifugal governor mechanism itself nor of the throttle valve mechanism being necessary after the units in question have been secured to the engine except such as involves the adjustment of the rod 36 to proper length by means of the threaded sleeve 35. It also follows 35 that one standard form of centrifugal governor mechanism unit and one standard form

of throttle valve unit or mechanism may be used with engines having different numbers 50 of cylinders, it being merely necessary in each particular case to provide a tube 68 and a connecting rod 36 of proper length to extend between the centrifugal governor unit and the throttle valve unit in the case of 55 each particular engine.

Having thus described and explained my invention, I claim and desire to secure by Letters Patent;

1. In governor mechanism of the class described, a hollow housing; centrifugal governor mechanism located within said housing and supported in its entirety therefrom; a pinion whereby said governor mechanism is driven; supporting means for supporting 65 said housing from the engine and in position such that said pinion will mesh with a gear of the engine, so that said mechanism may be attached to and removed from the engine in its entirety and as a single unitary device; a 70 mixture supply conduit through which combustible mixture flows to the engine; a valve for controlling the flow through said conduit; and a rod operated by said centrifugal governor mechanism and operatively connected with said valve. 75

2. In governor mechanism of the class described, centrifugal governor mechanism; means for driving said centrifugal governor mechanism; means whereby said centrifugal 80 governor mechanism in its entirety may be attached to and removed from an engine as a single unitary device, and which attaching mechanism is so constructed and arranged 85 that when said mechanism is secured to an engine the driving means therefor will be engaged by an element of the engine; a throttle valve adapted to control the flow of combustible mixture to the engine; and means intermediate said centrifugal governor mechanism and said throttle valve 90 through which the position of said throttle valve may be controlled.

In testimony whereof I affix my signature.

ARTHUR A. BULL.
